INDICATING SWITCH

Stuart H. Caldwell, Detroit, Mich., assignor to
 Kelch Heater Company, Detroit, Mich., a corporation of Michigan

Original applications August 31, 1936, Serial No. 98,810, and August 1, 1938, Serial No. 222,483. Divided and this application April 17, 1939, Serial No. 268,411.

18 Claims. (Cl. 200—56)

The present invention relates to an indicating switch and more particularly to a condition responsive indicator combined with a circuit controlling device operable in accordance with the value of the condition.

In the present application, the subject matter based on Figure 1 is a division of my prior application, Serial No. 98,810, "Tactual signal," filed August 31, 1936, now Patent No. 2,185,829, patented Jan. 2, 1940; that based on Figure 4, a division of my prior application, Serial No. 222,483, "Speed responsive switch," filed August 1, 1938.

According to one embodiment of the present invention, a condition responsive indicating device, such for example as a speedometer, has associated therewith a circuit making and breaking device comprising an adjustable contact carried by the casing of the indicator and a second contact movable with the indicating element of the device. According to the other embodiment of the present invention the condition responsive and indicating device has associated therewith a multiple switch comprising two pairs of contacts related such that one pair of contacts is automatically opened just prior to closure of the second pair of contacts.

It is an object of the present invention to provide a switch actuated by a movable indicating member of a condition responsive indicator.

It is a further object of the present invention to provide a switch closed by a movable part of an indicator and retained in circuit closing position throughout a predetermined range.

It is a further object of the present invention to provide a pair of integrally related switches associated with a condition responsive and condition indicating device.

It is a further object of the present invention to provide a pair of integral switches associated with a condition indicating device, together with means operable to open one switch as the other switch is closed.

It is a further object of the present invention to provide a switch associated with the condition indicating device, together with means for indicating the value of the condition at which said switch will operate.

It is a further object of the present invention to provide a condition responsive switch associated with an indicator having a dial, together with means for adjusting the switch relative to the dial to cause operation of said switch at various values of the condition, and means cooperating with the dial for indicating thereon the

value of the condition at which said switch will operate.

Other objects of the invention will be apparent as the description proceeds, and when taken in conjunction with the accompanying drawings, 5 wherein:

Figure 1 is a vertical section through one modification of my invention;

Figure 2 is a section on the line 2—2, Figure 1;

Figure 3 is a front elevation of my device with 10 parts broken away;

Figure 4 is a vertical section through another embodiment of my invention;

Figure 5 is a front elevation with parts broken away;

Figure 6 is an enlarged fragmentary perspective of a portion of my device;

Figure 7 is a detail sectional view of another portion of my device; and

Figure 8 is yet another detail sectional view. 20

The indicating switches disclosed herein are capable of numerous applications. In conformity with the patent statutes, I have chosen to illustrate specific embodiments thereof as controlling a signal device in an automotive vehicle, 25 and the condition responsive and indicating device illustrated is, in the present instance, a speedometer.

Referring first to Figures 1 to 3, the signal is operated by a speed indicator resembling a 20 tachometer of the fly-ball governor type. The tachometer is shown in Figure 1 as comprising a casing 10 having a dial 11 secured to the forward end thereof and having a needle 12 supported in advance of the dial for movement across the face 35 of the same. The needle 12 is secured to the forward end of a shaft 13 journalled in the front wall of the casing and having the rear end operatively connected to a fly-ball governor 14 through the medium of reduction gearing 15. 40 The governor 14 is of conventional construction having a shaft 16 journalled in opposite side walls of the casing and having collars supported upon the shaft in axial spaced relationship for relative movement toward and away from each 45 other. In the present instance, the collar 17 is secured to the shaft 16 and the opposed collar 18 is mounted on the shaft for axial sliding movement relative thereto. The two collars are interconnected by means of the weight carrying links 50 19, and the collar 18 is normally urged in a direction away from the collar 17 by means of a coil spring 20 surrounding the shaft 16 between the collars. In accordance with conventional practice, the weight carrying links are arranged in 55

pairs having their outer ends respectively pivotally connected to the collars and having their inner ends pivotally connected through the medium of centrifugal weights 21.

5 The weights 21 move radially outwardly with respect to the axis of the shaft 16 in dependence upon the speed of rotation of the shaft and, as the weights are displaced outwardly by the action of centrifugal force, the collar 18 is moved 10 against the action of the spring 20 toward the collar 17. Upon reference to Figure 1, it will be noted that the collar 18 is operatively connected to the reduction gearing 15 by means of a crank 22 having a pin 23 at one end journalled in a 15 partition 24 in the casing and secured to the drive gear 25 of the train of reduction gearing 15. The crank 22 is provided with a second pin 26 at the other end extending in a direction opposite to the direction of the pin 23 and engageable within an annular groove 27 formed in the collar 18. The arrangement is such that movement of the collar 18 axially toward the collar 17, under the influence of the weights 21, effects a swinging movement of the needle 12 20 over the face of the dial 11 through the train of gearing 15. It may be pointed out at this time that the ratio of the gearing 15 is such as to move the needle 12 one complete revolution over the dial when the collar 18 is moved to its fullest 25 extent by the weights 21.

The shaft 16 of the governor is rotated from a selected part of the power plant of the vehicle through the medium of a conventional driving cable 28 operatively connected to a spirally toothed gear 29 journalled within the casing and meshing with corresponding spiral teeth 30 on the shaft 16. Owing to the fact that the diameter of the gear 29 is substantially greater than the tooth portion 30 of the shaft 16, it 35 necessarily follows that the shaft 16 is rotated at a speed proportionately faster than the speed of the driving cable. This practice is usually followed in order to afford greater accuracy in indicating the speed of the vehicle.

40 It has been indicated above that the device briefly referred to is employed to operate a signal indicated generally at 37, and this is accomplished herein without appreciably altering the construction or operation of the device. Referring again to Figure 1, it will be noted that a 45 contact segment 31 is secured to the needle shaft 13 in rear of the needle 12 for rotation therewith as a unit and having the peripheral portion thereof adapted to engage a cooperating contact clip 32 supported upon the forward end of the casing for circumferential adjustment.

The contact segment 31 is grounded through the casing as indicated by the reference character 33, and the contact 32 is located in an 50 electric circuit including the signal 37. The arrangement is such that the segment 31 cooperates with the contact clip 32 to form in effect a switch for controlling the operation of the signal in dependence upon the extent of rotation of the needle shaft 13.

55 Reference has been made in the above to the fact that the operator is permitted to preselect the speed at which the signal is adapted to operate, and this is accomplished herein by circumferentially adjusting the contact 32 relative to the dial 11. As shown in Figure 1, the contact 32 is secured to a ring 45 of dielectric material rotatably mounted on the casing 10 adjacent the dial 11 and having a series of rack teeth 46 on the 60 periphery thereof for engagement with a pinion 65

70 The pinion 47 is secured to a shaft 48 suitably journalled on the casing and having a knob 49 at the outer end thereof located for convenient manipulation by the operator. With the above construction, it will be obvious that the 75 contact 32 may be adjusted relative to the contact 31 throughout the circumferential extent of the dial 11, and thereby renders it possible to effect operation of the signal at practically any particular speed of travel. It will be observed 80 from Figure 3 that the contact 32 is visible through the front end of the indicator and, accordingly, the indicia on the dial 11 may be employed to guide the operator in setting the contact at the desired speed. 15

I have illustrated in Figures 4 to 8 a second embodiment of my invention in which a multiple switch is associated with my indicating condition responsive device.

A two-stage signal or the like indicated at 111 20 in Figure 4 is adapted to be connected to a source of current 147 by wire 112 which is connected to contacts 152 and 159. A pivoted armature carrying spaced contacts 150 and 158 is mounted adjacent contacts 152 and 159 and is adapted alternately to complete a circuit from source 147 25 to device 111 through wires 113 and 114. Wire 113 has a resistance element 151 therein, for reducing the effectiveness of device 111.

Line 112 is further connected to two coils 146 30 and 157 in parallel relation, and the coils are connected by wires 170 and 171, respectively, to circuit making and breaking devices subsequently to be described. At present it is sufficient to observe that the circuits through coils 35 146 and 157 are completed serially (i. e. first one and then the other), and the circuit through coil 146 is open just prior to closure of the circuit through coil 157.

Source 147 is grounded as at 148, device 111 40 is grounded at 153, and the circuits through coils 146 and 157 are eventually grounded at 145. Coils 146 and 157, if required, may include suitable resistance elements to insure a definite flow of current through device 111. 45

The associated switch and speedometer shown generally at 115 in Figure 4 comprises a speedometer of the fly-ball governor type supported on the instrument panel of the body in a position to be readily observed by the operator. The speedometer is shown in Figure 4 as comprising a casing 116 having a dial 117 secured to the forward end of the casing in any suitable manner and having a needle 118 supported in advance of the dial for movement across the face of the same. 55 The needle 118 is secured to the front end of a shaft 119 journalled in the front wall of the casing and having the rear end operatively connected to a fly-ball governor 120, through the medium of suitable reduction gearing 121. The 60 governor 120 is of conventional construction having a shaft 122 journalled in opposite side walls of the casing and having collars supported on the shaft in axial spaced relationship for relative movement toward and away from each other. In 65 the present instance, the collar 123 is secured to the shaft 122, and the opposed collar 124 is mounted on the shaft for axial sliding movement relative to the collar 123. The two collars are interconnected by means of weight carrying links 70 125, and the collar 124 is normally urged in a direction away from the collar 123 by means of a coil spring 126 surrounding the shaft 122 between the collars. In accordance with conventional practice, the weight carrying links are arranged 75

in pairs having their outer ends respectively pivotally connected to the collars and having their inner ends pivotally connected together through the medium of centrifugal weights 127. The 5 weights 127 move radially outwardly with respect to the axis of the shaft 122 in dependence upon the speed of rotation of said shaft and, as the weights are displaced outwardly by the action of centrifugal force, the collar 124 is moved against the action of the spring 120 toward the collar 123. As shown in Figure 4, the collar 124 is operatively 10 connected to the drive gear 128 of the reduction gearing 121 by means of a crank 129 having the crank pin 130 engageable in an annular groove 131 formed in the collar 124. The arrangement 15 is such that movement of the collar 124 axially toward the collar 123, under the influence by the weights 127, effects a swinging movement of the needle 118 over the face of the dial 117 through the medium of the crank 129 and train of gearing 121. The governor shaft 122 is rotated from a selected part of the power plant of the vehicle through the medium of a conventional speedometer drive cable 131' operatively connected to a 20 shaft 132 journalled in the casing 116 and having a spirally toothed gear 133 secured thereto and meshing with correspondingly spiralled teeth on the governor shaft 122. Owing to the fact that the diameter of the gear 133 is substantially 25 greater than the tooth portion of the shaft 122, it necessarily follows that the shaft 122 is rotated at a speed faster than the speed of the driving cable, and this practice is desirable in that it affords greater accuracy in indicating the speeds 30 of the vehicle.

It has previously been stated that the device 111 is actuated by the speedometer 115, and this is accomplished herein without appreciably altering the construction of the speedometer unit. As 40 shown in Figure 4, a contact segment 135 is secured to the indicating needle shaft 119 for rotation therewith as a unit and adapted to engage a contact clip 136 secured to a ring 137 of dielectric material rotatably mounted on the forward end of the casing 116 and having teeth on the periphery thereof adapted to mesh with a pinion 138 secured to the control shaft 139. The control shaft 139 is rotatably journalled on the casing and is provided with a control 140 positioned for convenient 45 manipulation by the operator. The arrangement is such that manipulation of the control 140 varies the position of the contact clip 136 relative to the segment and this, of course, changes the speed at which the two contacts come into engagement with each other. In Figure 5 of the drawings, the segment is shown in a position where it has just engaged the contact clip 135, and it will be noted from this figure that the segment is so designed as to maintain this engagement 50 throughout continued travel of the needle 118 in the direction of the arrow 141. It will be noted that the forward end of the contact clip 136 terminates in a pointer 142 adapted to overlap the dial 117 and cooperates with the indicia on the dial to guide the operator when selecting the particular speed he desires the signal to function. For example, if the operator desires to be warned 55 when the vehicle exceeds fifty miles per hour, the contact clip is adjusted until the pointer registers with the numeral 50 on the dial 117. This locates the contact clip 136 in a position to be engaged by the leading edge of the contact segment when this edge is moved by the needle shaft 119 to a position wherein it also registers with the numeral 50. As will be presently described, en-

gagement of the cooperating contacts closes the circuit to the device 111 through wire 113 and the latter acts at a constant intensity.

The contact segment 135 is grounded through the casing 116 in the manner indicated by the 5 reference character 145, and the contact clip 136 is electrically connected to one end of the coil 146.

Assuming that the contact segment moves into engagement with the contact clip 136, it will be 10 noted that a circuit is closed through the coil 145, and energization of the latter causes the contact 150 to engage the contact 152. When this is accomplished, electrical energy is supplied through 15 the line 113 to the device 111.

Reference has been made to the fact that the intensity of the warning signal is increased when the speed of the vehicle substantially exceeds the preselected speed. The foregoing is accomplished in the present instance by providing a 20 second contact clip 136' secured to the ring 137 adjacent the clip 136 and engageable with a second segment 135' secured to the needle shaft 119 for rotation as a unit with the segment 135. It will be observed from Figure 5 that the leading 25 edge 155 of the segment 135' is spaced from the corresponding edge of the segment 135 in a direction opposite the direction of rotation indicated by the arrow 141. As a consequence, the segment 135' contacts with the clip 136' after the clip 136 30 engages the segment 135 to actuate the signal 111. Just prior to engagement of the clip 136' with the contact segment 135', the insulating ring 155' on the periphery of the segment 135' engages a shoulder 160 formed on the clip 136 and disengages the latter from the segment 135 to break the circuit to the signal 111. Immediately after the clip 136 is disengaged from the segment 135 by the segment 135', an arcuate cam 156 on the front side of the latter contacts with the clip 136' 40 in the manner shown in Figure 6, and closes a circuit including wire 171 to the coil 157 of the second relay. Energization of the coil 157 causes the contact 158 on the end of the armature 149 opposite the end having the contact 150, to engage the coil contact 159 and supply electrical energy through line 114 to the device 111. The resistance 151 in the conductor connecting the contact 150 to this button contact is omitted in the electrical connection of the contact 158 with 50 the signal, so that a circuit of higher amperage is supplied to the device 111.

While I have illustrated and described several specific embodiments of my invention, it will be apparent to those skilled in the art that various 55 additions, modifications, omissions, combinations and substitutions may be made which will be within the spirit and scope of my invention as defined by the appended claims.

What I claim as my invention is:

1. A condition responsive switch comprising a casing having a cylindrical front portion, a circular track adjacent said front portion, a ring of insulating material rotatably mounted in said track, a contact carried by said ring, teeth on said ring, and a manually rotatable pinion meshing with said teeth, condition responsive means in said casing, a movable contact actuated by said condition responsive means, and movable in a path to engage said first mentioned contact.

2. A condition responsive switch comprising a cylindrical casing having a dial provided with indicia, a circular track on said casing, a ring of insulating material rotatably mounted in said track, a contact carried by said ring, having a

contact portion in the rear of said dial and a pointer extending to the face of said dial, condition responsive means in said casing, a movable contact in the rear of said dial actuated by said condition responsive means, and movable in a path to engage said first mentioned contact, and an indicator movable with said movable contact in front of said dial to indicate the position of said movable contact relative to said indicia and 10 said first mentioned contact.

3. A condition responsive switch comprising a casing having a cylindrical front portion, a circular track adjacent said front portion, a ring of insulating material rotatably mounted in said track, a contact carried by said ring, condition responsive means in said casing, a movable contact actuated by said condition responsive means, and movable in a path to engage said first mentioned contact, said movable contact being in the 15 shape of a segment of a circle and centrally pivotally mounted, to establish and maintain engagement with said first mentioned contact at and above a predetermined value of said condition.

4. A condition responsive switch comprising a casing having a circular face, condition responsive means in said casing, a shaft rotatably mounted centrally of said face and extending therethrough, connections between said condition responsive means and said shaft for rotating said shaft to positions depending on the value of said condition, a segmental circular contact disk fixed to said shaft exterior of said casing, the periphery of said contact disk terminating adjacent the edge of said face, a plate secured to said casing, spaced outwardly from said contact disk, said plate being centrally apertured to receive said shaft, a pointer fixed on said shaft, movable over said plate, an insulating ring carried by said casing adjustable around the periphery of said face, a contact carried by said ring, in a position to be engaged by said contact disk, a portion of said contact extending inwardly over said plate, graduations in terms of said condition on said 45 plate for cooperation with said pointer and said inwardly extending portion of said contact.

5. An indicator switch comprising a dial, an indicating pointer movable over said dial, a resilient contact adjacent said dial having a pointer 50 cooperating with said dial, a contact member movable with said indicating pointer and adapted to engage said resilient contact when said indicating pointer and the pointer on said resilient contact are matched, said contacts adapted to remain in contact upon further movement of said indicating pointer, and means movable with said indicating pointer for thereafter moving said resilient contact away from said contact member.

6. An indicator switch comprising a dial, an indicating pointer movable over said dial, a resilient contact adjacent said dial having a pointer 55 cooperating with said dial, a contact member movable with said indicating pointer and adapted to engage said resilient contact when said indicating pointer and the pointer on said resilient contact are matched, said contacts adapted to remain in contact upon further movement of said indicating pointer, and means movable with said indicating pointer for thereafter moving said resilient contact away from said contact member, said means comprising a cam surface engageable with said resilient contact.

7. An indicator switch comprising a dial, an indicating pointer movable over said dial, a resilient contact adjacent said dial having a pointer 70

cooperating with said dial, a contact member movable with said indicating pointer and adapted to engage said resilient contact when said indicating pointer and the pointer on said resilient contact are matched, said contacts adapted to remain in contact upon further movement of said indicating pointer, means movable with said indicating pointer for thereafter moving said resilient contact away from said contact member, a second contact adjacent said dial, and a second contact 10 member movable with said indicating pointer, and adapted to engage upon disengagement of said first pair of contacts.

8. An indicator switch comprising a dial, an indicating pointer movable over said dial, a resilient contact adjacent said dial having a pointer 15 cooperating with said dial, a contact member movable with said indicating pointer and adapted to engage said resilient contact when said indicating pointer and the pointer on said resilient 20 contact are matched, said contacts adapted to remain in contact upon further movement of said indicating pointer, means movable with said indicating pointer for thereafter moving said resilient contact away from said contact member, a second contact adjacent said dial, and a second contact member movable with said indicating pointer, and adapted to engage upon disengagement of said first pair of contacts, said resilient contact and said second contact being adjustable as a unit 25 peripherally of said dial.

9. Circuit control means comprising a cylindrical casing having a dial at one end, an indicating pointer movable over said dial, a ring of insulating material rotatably mounted on said casing adjacent said dial, means for adjusting said ring, a first and second contact carried by said ring, a first and second contact member movable with said pointer and cooperating with said first and second contacts respectively, and means movable with said second contact member for disengaging said first contact and said first contact member just prior to engagement of said second contact and said second contact member.

10. Circuit control means comprising a cylindrical casing having a dial at one end, an indicating pointer movable over said dial, a ring of insulating material rotatably mounted on said casing adjacent said dial, means for adjusting said ring, a first and second contact carried by 50 said ring, a first and second contact member movable with said pointer and cooperating with said first and second contacts respectively, and means movable with said second contact member for disengaging said first contact and said first contact member just prior to engagement of said second contact and said second contact member, said first contact comprising a resilient element having an indicating portion movable over said dial.

11. Circuit control means comprising a cylindrical casing having a dial at one end, an indicating pointer movable over said dial, a ring of insulating material rotatably mounted on said casing adjacent said dial, means for adjusting 65 said ring, a first and second contact carried by said ring, a first and second contact member movable with said pointer and cooperating with said first and second contacts respectively, and means movable with said second contact member for disengaging said first contact and said first contact member just prior to engagement of said second contact and said second contact member, said means comprising a cam carried by said second contact member.

12. A condition responsive switch comprising a cylindrical casing, a dial having indicia thereon carried by said casing, an indicating pointer movable over said dial, condition responsive means 5 in said casing, connections intermediate said condition responsive means and said indicating pointer, a contact behind said dial movable with said pointer, a resilient contact adjustably mounted on the periphery of said casing, said 10 resilient contact having a contact portion in rear of said dial engageable with said first contact and a pointer portion extending radially inward over said dial.
13. In a condition responsive switch having a dial 15 having indicia thereon and an indicating needle movable over said dial, a contact movable with said indicating needle in rear of said dial, an adjustable contact having a portion adapted to be engaged by said first contact, said adjustable contact being located in back of said dial and having a pointer extending forwardly and radially inwardly of said dial to cooperate with the indicia thereon.
14. A condition responsive switch comprising a casing 20 having a cylindrical front portion, a circular track provided in the periphery of said casing, a ring of insulating material rotatably mounted in said track, a contact carried by said ring, condition responsive means in said casing, a movable contact actuated by said condition responsive means and engageable with said first contact, manually operable means for adjusting said ring in said track, a dial having indicia at the front of said casing and concealing said movable contact, and a pointer movable with said ring over 25 said indicia.
15. An indicator switch comprising a dial, an indicating pointer movable over said dial, a contact at the rear of said dial movable with said pointer and having a portion extending adjacent the periphery of said dial, a resilient contact having a contact portion adjacent the periphery of 30
- 40

said dial in position to be engaged by said first contact and having an indicator portion extending over the periphery of said dial into cooperative relation with the dial.

16. An indicator switch comprising a casing 5 having a dial provided with indicia adjacent one edge, said dial having an opening therethrough, a shaft in said opening, an indicating pointer secured to said shaft at the front of said dial, a contact secured to said shaft at the rear of said dial having an arcuate contact portion extending adjacent the said edge of said dial, a resilient contact having a portion adjacent the said edge of said dial in position to be engaged by said first contact, said resilient contact extending forwardly across the said edge of said dial and having a pointer portion extending inwardly over the front of said dial to cooperate with the said indicia thereon.

17. An indicator switch comprising a dial 20 having indicia thereon, a pointer movable over said dial in cooperation with said indicia, a contact movable with said pointer at the rear of said dial adjacent said indicia, and a resilient contact extending generally perpendicular to said dial 25 and having a portion at the rear of said dial in the path of said movable contact and a bent pointer portion at the front of said dial cooperating with said indicia.

18. An indicator switch comprising a dial having 30 indicia thereon, adjacent an edge of said dial, a pointer rotatable over said dial in cooperation with said indicia, a contact rotatable with said pointer at the rear of said dial adjacent said indicia, and a resilient contact extending generally perpendicular to said dial and extending across the said edge of said dial, said resilient contact having a portion at the rear of said dial in the path of said rotatable contact and a bent pointer portion at the front of said dial cooperating 35 with said indicia.

STUART H. CALDWELL.
